[57] CLAIM

The ornamental design for a shelf support, as shown and described.

DESCRIPTION

FIG. 1 is a top, left, front perspective view of a first embodiment of a shelf support showing the design of the present invention;

FIG. 2 is a left side view thereof;

FIG. 3 is a front view thereof;

FIG. 4 is a right side view thereof;

FIG. 5 is a back view thereof;

FIG. 6 is a top view thereof;

FIG. 7 is a bottom view thereof;

FIG. 8 is a top, left, front perspective view of a second embodiment of a shelf support with left side shield showing the design of the present invention;

FIG. 9 is a left side view thereof;

FIG. 10 is a front view thereof;

FIG. 11 is a right side view thereof;

FIG. 12 is a back view thereof;

FIG. 13 is a top view thereof;

FIG. 14 is a bottom view thereof.

FIG. 15 is a top, left, front perspective view of a third embodiment of a shelf support with right side shield showing the design of the present invention;

FIG. 16 is a left side view thereof;

FIG. 17 is a front view thereof;

FIG. 18 is a right side view thereof;

FIG. 19 is a back view thereof;

FIG. 20 is a top view thereof; and,

FIG. 21 is a bottom view thereof.

The broken line showing of a partial shelf is for illustrative purposes only and forms no part of the claimed design.
